UNITED STATES PATENT OFFICE.

ROBERT J. CARTMELL, OF SOAP LAKE, WASHINGTON, ASSIGNOR OF ONE-HALF TO JOHN W. KAHL, OF SEATTLE, WASHINGTON.

PUMPING DEVICE.

1,216,415.

Specification of Letters Patent.

Patented Feb. 20, 1917.

Application filed April 24, 1916. Serial No. 93,084.

To all whom it may concern:

Be it known that I, ROBERT J. CARTMELL, a citizen of the United States, and resident of Soap Lake, Grant county, Washington, have invented certain new and useful Improvements in Pumping Devices, of which the following is a specification.

My invention relates to pumps and to a pump of a kind which is particularly adapted for use in deep wells. My invention also includes the mechanism employed for operating such a pump.

The object of my invention is to provide a pump which is particularly adapted for use in deep wells and means for operating it such that the column of water, when set in motion, will continue moving without any halting between strokes and at substantially uniform speed at all times. The above object is attained by the use of a special kind of pump and by operating this by means of mechanism of a special type. Other objects of my invention will appear from a study of the specifications and the claims. The scope of my invention may also be determined by an examination of the claims terminating this specification.

In the accompanying drawings I have shown my invention embodied in the form of construction which is now most preferred by me.

Figure 1 is an elevation, partly in section, of a deep well having therein a pump made and operated in accordance with my invention.

Fig. 2 is an elevation taken through the pit at the upper end of the well in which the pump actuating mechanism is installed, the view thereof being taken from a point at right angles to Fig. 1.

Fig. 3 is a sectional elevation taken from the same view point as in Fig. 1.

Fig. 4 is a vertical section through the upper end of the pump casing showing the discharge and the packing gland surrounding the pump rod.

Fig. 5 is a horizontal section taken on the center line of the pump discharge.

In my pump I preferably locate the cylinder at the bottom of the well, or at least at such a point that the natural head of the water will cause the water to flow thereto at all times.

The cylinder 1 is provided with a foot valve 10 at the lower end thereof, or at a

point which is beyond the farthest point reached in the stroke of the piston. The piston 2 is provided with a valve or valves 20, through which the water may pass from one side of the piston to the other. The pump 60 casing 11 is of substantially the same sectional area as the sectional area of the section 1 which constitutes the cylinder. This casing extends to the surface.

The piston or pump rod 21, is made of a 65 cross-sectional area substantially half that of the piston 2 and also substantially half that of the delivery pipe or casing 11 and extends at this diameter to the surface and through the packing gland 22. The length 70 of this pipe is such that an end is at all times projected beyond the packing gland, even when the piston is at its extreme lowermost point.

In using a pump of this kind, it is intended 75 that the pump piston be actuated at a uniform rate from start to finish, that is, that the start and stop be promptly made and the speed of operation be quickly attained and maintained throughout the 80 stroke and that the period of rest be as short as possible. When so operated, the following results will be secured: On the upward movement of the piston an amount of water is drawn in through the foot valve 85 10 to fill the cylinder 1; the amount of water discharged through the discharge pipe 12 to the top of the well will be equal to half the volume of the water contained in the casing for any unit of length, as its displacement is just half that of the same 90 length of cylinder. This follows from the fact that the pump rod 21 is in area equal to half that of the casing or delivery pipe 11.

On the downward movement of the pump 95 piston the water which is contained in the cylinder 1 between the piston 2 and foot valve 10, will be forced through the valves 20 in the piston into the delivery pipe 11. As the extra displacement produced in the 100 casing 11 and cylinder 1 by the downward movement of the piston is only that due to the size of the pump rod 21, and as this extra displacement is in volume one-half that due to the travel of the piston, then a 105 volume of water equal to half the contents of the cylinder will be forced upward and outward through the discharge pipe 12 by such downward movement. It is thus seen that this pump, although having only a foot 110

valve and a valve in the piston, acts to produce an equal discharge upon the movement of the piston in either direction. It thus, in effect produces constant and continuous delivery of water, although resembling in its construction a single acting pump.

In operating this pump it is desirable that the speed of travel of the piston be sufficiently high that the momentum of the column of water in the casing will be sufficient to cause it to continue its motion to a considerable degree during the slight pause or interval which must elapse at the time of reversal of the stroke of the pump. As this time is very short, the pump may, by operating it at the proper speed, be caused to discharge a continuous, steady stream of water, and that without necessity for employing an air chamber. For the most successful operation of this pump, it is therefore necessary to employ a mechanism which will secure this prompt reversal and uniform rate of movement during the stroke. To this end I prefer to employ a type of mechanism which is substantially the same as that shown in Patent No. 1,169,923, issued to me February 1, 1916.

This mechanism employs a yoke 3 which consists of two parallel bars joined at their ends and having rack teeth formed upon their inner or opposite faces and a pinion 4 which is adapted to engage one of these racks at a time and upon reaching the end of a rack is automatically transferred to engage with the opposite rack, such mechanism being, in its general features a well known type of mechanism for converting rotary into reciprocating movement. In the device employed the yoke 3 is provided with lugs 30, located at the ends thereof and outwardly of the side edges of the pinion and the pinion 4 is provided with lugs 40 at opposite sides to engage with lugs 30 of the yoke, to thereby shift the yoke laterally. The mechanism for operating this yoke is essentially shown in the said patent and its description in detail herein is therefore believed to be unnecessary.

The connection of this pump actuating mechanism with the pump rod is however slightly different from that shown in the said patent. The upper end of the pump rod 21 is provided with a head which contains a pin 23 and the lower end of the yoke 3 is provided with a transversely extended slot 31, which receives the pin 23. The transverse horizontal extent of this slot is such as to accommodate the transverse shift of the yoke on reversal. The slot is also placed at a slight angle to the horizontal, the direction of the angle being determined by the position occupied by the yoke when making either stroke. The position shown in Fig. 3 is that occupied at the time the yoke and pump are starting the upward

movement. It will be noted that the angular position of the slot 31 is such that the reciprocating movement of the yoke will tend to cause the pin 23 to slide into the end it is intended to occupy.

When the yoke reaches its uppermost position and is reversed for the downward stroke, it shifts laterally so that the pin 23 occupies the other end of the slot 31. It will be noted that the inclination is also such that the downward thrust of the yoke will tend to cause movement of the pin 23 into corresponding position in the slot; in other words, the inclination of the slot is such that the slight tendency produced by lengthwise movement of the yoke will tend to draw the pin toward the position it should occupy during this movement.

The upper end of the pump rod is preferably provided with guides of such character as to support it and cause it to move in a straight line. To this end the upper end of the pump rod is provided with a cross head 24 having arms 25, each provided with a hole fitting about a guide rod 26, which guide rod is supported at top and bottom.

To lessen the shock at the time of starting and stopping the pump rod, I prefer to provide the guide rods 26, at each end with a coil spring 27, against which the cross head arms 25 engage at the end of the stroke. The slight compression of these springs prior to reversal will give an impetus to the yoke sufficient to start it promptly upon the reverse stroke, thus cutting down the time required for the reversal. To assist the prompt lateral shifting of the lower end of the yoke 3 at the bottom limit of its stroke, I provide a spring 5 which is so shaped and placed that it has an inclined surface 50 at the inner side of its upper end, which constitutes a cam surface for engagement with the lower end of the yoke 3, thus exerting upon this yoke a lateral push which is effective, immediately upon the removal of the downward effort, to cause this end of the yoke to be shifted laterally into the desired position for the reverse stroke.

Experience has shown that in the operation of these pumps they may be given a speed of travel such that the momentum of the water will be ample to continue the movement of the water column throughout the period of reversal of the pump, without causing any appreciable slackening in its rate of movement, and also that the pump actuating mechanism described may be operated smoothly at the speeds needed to secure this result. In the operation of the pump it is necessary to employ some mechanism for operating it which will give this uniform rate of travel and prompt reversal in the ends of the stroke. The mechanism herein shown has proved to be the best adapted for that service of any yet tried.

What I claim as my invention is:

1. A pump operating mechanism comprising a pump rod guided to reciprocate in a fixed path, an actuating member for said rod comprising a yoke frame having opposite, inwardly facing racks, a rotating pinion adapted to be engaged with either rack, means for laterally shifting the yoke to engage its racks alternately with the pinion, and a means connecting said yoke with the pump rod permitting a lateral shifting of the point of connection to correspond with the lateral shifting of the yoke.
2. A pump operating mechanism comprising a pump rod guided to reciprocate in a fixed path, an actuating member for said rod comprising a yoke frame having opposite inwardly facing racks, a rotating pinion adapted to be engaged with either rack, means for laterally shifting the yoke to engage its racks alternately with the pinion, and a means connecting said yoke with the pump rod comprising a transversely extending slot in one and a pin in the other, whereby a transverse shifting of the point of connection is secured.
3. A pump operating mechanism comprising a pump rod guided to reciprocate in a fixed path, an actuating member for said rod

comprising a yoke frame having opposite 30 inwardly facing racks, a rotating pinion adapted to be engaged with either rack, means for laterally shifting the yoke to engage its racks alternately with the pinion and a means connecting said yoke with the 35 pump rod comprising a pin on the pump rod and a slot in the yoke, the slot in the yoke being inclined slightly from a perpendicular to the axis of reciprocation in a direction that the tendency for lateral movement due 40 to the angle corresponds with the lateral movement given the yoke when reversed.

4. The combination with a driving pinion, a yoke having opposite inwardly facing 45 racks adapted to be alternately engaged with the pinion, a driven member reciprocating in a fixed path, means acting upon the yoke adjacent the pinion to shift it laterally from engagement with the other, the driven member having a pin and the yoke having a 50 transversely extending slot receiving the pin, and a spring placed to engage the yoke to laterally shift it as it reaches the lowermost point of its travel.

Signed at Seattle, Washington, this 11th 55 day of April 1916.

ROBERT J. CARTMELL.
